SUCTION DEVICE FOR GASOLINE ENGINES

Susumu Hashimoto, Osaka City, Japan

Application October 25, 1937, Serial No. 170,943
In Japan October 27, 1936

2 Claims. (Cl. 48—180)

This invention relates to a suction device for gasoline engines characterized by the feature that a vane wheel is rotatably journaled within the suction passage between the carburetor and the intake manifold, at right angles to the direction of suction, so that the gas mixture may be passed up into the exhaust manifold while being subjected to the beating action of the vane wheel.

This invention has for its object to provide a suction device wherein the gas may be super-atomized under the beating action of the vane wheel, and also may be completely blended with air, so that an ideally complete combustion of the gas mixture is made possible by a very simple means.

Further objects of the invention are to economize the fuel oil; to offer a method by which a low grade of fuel can be used effectively, without reducing the engine efficiency; and finally to substantially increase the engine efficiency.

Due to the complete combustion as realized by the invention the exhaust gas is colourless, and odourless, and further is free from carbon particles being deposited on the ignition plug.

Petroleum or neutral oil, as well known, contains more heat units than gasoline, but they have not been used as fuels for gasoline engines, because of the bad condition in which they are brought to a combustion. Further it may be insisted that even gasoline can not be brought to a complete combustion by employing the heretofore known devices. This is because of the fact that such technical advance has not yet been made by which the fuel generally, regardless of its quality or grade, may be completely burned; and further difficulties are found in admixing the fuel with air.

These difficulties are avoided by the invention. According to the invention, a fuel of high grade, viz. gasoline can be more effectively vaporized than heretofore, and at the same time can be ideally admixed with air. According to the invention, a fuel of low grade, such as petroleum or neutral oil, can be easily vaporized, and it is therefore made possible to use such low grade fuels instead of gasoline, or in admixture with gasoline. Consequently, a material economy of fuel expense is obtained.

The invention essentially consists in that the gas discharged from the carburetor can be super-atomized and blended with air completely.

Referring to the accompanying drawing, illustrating several embodiments of the invention, Fig. 1 is a front view, with parts broken off, of the suction device made in accordance with the invention; Fig. 2 shows in a section on the line 2—2 of Fig. 1; Fig. 3 is a perspective view of the vane wheel.

There is arranged between the carburetor and

the suction pipe 2, a vane wheel casing 9 provided with a lateral wall bulged outwardly, and in the interior of the casing the vane wheel 5 is journaled eccentrically to the suction passage and also at right angles to the direction of suction *a*. The vane wheel 5 is subjected to the suction from the cylinder of the engine and is set in self-rotating motion. The number of revolutions of the vane wheel is proportional to the suction capacity compared to the cylinder stroke. An experiment has been made of a 1931 type Chevrolet car engine with six cylinders and with 3390 c. c. cylinder volume. The result is shown in the following table:

	Revolutions per minute of crank shaft	Revolutions per minute of vane wheel
Minimum speed working.....	200	2,800—5,300
Maximum speed working.....	1,500	21,000—40,000

The diameter of the vane wheel employed in the experiment is two inches.

In this construction the gas pressure is exerted upon the vane wheel on one of its lateral sides only, making it possible to increase number of revolutions of the vane wheel, and consequently to further make active the beating action of the vane.

In Fig. 3 is shown the vane wheel which is composed of alternate flat perforated and imperforated blades 4' and 4'' for the purpose of deflecting the gas in passing the wheel, the gas after passing through the perforated blades 4' is deflected by impinging upon the next imperforated blade 4''. This assures thorough atomization of the liquid fuel.

I claim:

1. A suction device for gasoline engines characterized by the fact that within a branch pipe of the intake manifold which is in communication with the carburetor there is rotatably journaled a vane wheel at right angles to the direction of suction, whereby the vane wheel is made to be subjected to the suction of the cylinder and set in self-rotatory motion for the purpose as specified, said vane wheel comprising a plurality each of alternately disposed radial perforated and imperforated blades.

2. A suction device for gasoline engines characterized by the fact that within a vane wheel casing disposed between the carburetor and the suction pipe, there is journaled a vane wheel disposed eccentrically to the direction of suction, said vane wheel comprising a plurality each of alternately disposed radial perforated and imperforated blades.
